UNITED STATES PATENT OFFICE.

ADOLPH STUBER, OF ROCHESTER, NEW YORK, ASSIGNOR TO EASTMAN KODAK COMPANY, OF ROCHESTER, NEW YORK, A CORPORATION OF NEW YORK.

DESIGN FOR A CAMERA COVERING.

Application filed June 28, 1926. Serial No. 18,205. Term of patent 14 years.

To all whom it may concern:

Be it known that I, ADOLPH STUBER, citizen of the United States, residing at Rochester, in the county of Monroe and State of New York, have invented a new, original, and ornamental Design for Camera Covering, of which the following is a specification, reference being had to the accompanying drawing, forming a part thereof.

In the drawings Fig. 1 is a back elevation of a camera covering showing my new design;

Fig. 2 is a side elevation; and
Fig. 3 is a front elevation of the camera covering shown in Fig. 1.

I claim:

The ornamental design for a camera covering, as shown.

Signed at Rochester, New York, this 24 day of June, 1926.

ADOLPH STUBER.
